UNITED STATES PATENT OFFICE.

ALBERT E. ABEL, OF SHARPSVILLE, PENNSYLVANIA, ASSIGNOR TO VALLEY MOULD & IRON CORPORATION, OF SHARPSVILLE, PENNSYLVANIA, A CORPORATION OF NEW YORK.

INGOT MOLD.

Application filed December 30, 1920, Serial No. 433,978. Renewed April 5, 1924.

To all whom it may concern:

Be it known that I, ALBERT E. ABEL, a citizen of the United States, residing at Sharpsville, in the county of Mercer, State 5 of Pennsylvania, have invented certain new and useful Improvements in Ingot Molds, of which the following is a specification.

This invention relates broadly to molding and more specially to the improvements 10 in horizontal ingot molds.

The principal object of the present invention is an ingot mold for casting horizontal ingots wherein a conduit comprising a runner for the mold is supported by the mold 15 body.

A more specific object of the present invention is an ingot mold provided with a conduit set in the wall of the mold and adapted to direct molten metal into the mold 20 adjacent the bottom thereof.

A further and important object of the present invention is an ingot mold of cast iron or the like and provided with a channel into which a fire clay runner is adapted 25 to be set in such manner that the walls of the mold support the runner and with a cover having a suitable recess provided for supporting and retaining the upper end of the runner in communication with a 30 fountain to direct molten metal in the mold.

Another and more specific object of the present invention is an ingot mold adapted for casting horizontal ingots and comprising 35 a body portion having a channel extending from the matrix of the ingot mold in such manner as to receive a suitable runner tile of fire clay or the like with one face of said tile being adapted to comprise a portion of the side wall of the finished 40 matrix of the mold.

A still further object of the present invention is an ingot mold for horizontal ingots comprising a body portion having channels at each end thereof with one channel 45 adapted to receive a suitable fire clay or the like runner and the other channel adapted to receive a suitable fire clay conduit or the like for the escape of gases from the mold.

50 Still more specifically the present invention comprises an ingot mold for horizontal ingots or the like wherein a body portion of the mold is provided on each end with suitable channels adapted to receive fire

clay conduits with one conduit opening into 55 the matrix portion of the mold adjacent the bottom thereof and comprising a runner conduit, the other conduit opening into the matrix portion adjacent the upper part thereof and comprising a gas outlet. 60

Other objects and advantages of the present invention will be pointed out herein-after in the specification following by reference to the accompanying drawings in 65 which like characters will be used to represent like parts throughout the several figures thereof.

In view of the fact that the present invention may be embodied in constructions other than those specifically shown and described it is to be understood that the present disclosure is merely illustrative of one embodiment of the invention and is not to be considered in the limiting sense. 70

Figure 1 is a sectional view on line 1—1 of Figure 2. 75

Figure 2 is a plan view of the device showing the cover in position on the mold.

Figure 3 is a plan view of the body of the mold with the cover removed but showing 80 a runner and a gas outlet in position.

Figure 4 is a sectional view on line 4—4 of Figure 2.

Figure 5 is a sectional view on line 5—5 of Figure 1. 85

Heretofore in the art of casting steel ingots it has been customary to cast the ingots by either pouring the metal directly into the open mold or by providing runners wherein the runner column is built up outside of the mold structure and wherein the column leads under the mold body and into the matrix thereof. In molds where the metal is poured directly into the mold it is difficult to fill the mold exactly to contact with a suitable cover where it is desired to chill all of the surfaces of the ingot. As a matter of fact it is substantially impossible to cast uniform sized full chilled ingots by pouring into open molds. In the mold wherein an outside runner column is provided and the metal runs through the column and under the mold body, the metal is compelled to traverse a considerable length of the conduit and there is a liability of chilling and choking the conduit or else choking the conduit to such an extent that full flow is interrupted. Furthermore the runner conduits leave stubs of 90 95 100 105

metal attached to the ingot and these stubs must be broken before the ingot is used. Where the outside runners are utilized the stubs are quite long thereby producing a relatively large amount of undesirable scrap and rendering the breaking off process necessary before the ingot can be handled for transportation to the soaking pit or other handling which may be necessary. Where 10 outside runners are utilized it is necessary to brace up the runner tiles sufficiently to insure stability of the runner during pouring, and it also requires the forming of several angular joints by means of runner tiles. The 15 forming of joints is troublesome and requires either special tiles or special cutting of tiles to secure the right lengths and accurate fitting. Furthermore the outside runner columns require considerably more floor 20 space than is required for the mold bodies alone.

The present invention overcomes the difficulties of the known art by providing a mold with the runner column supported directly 25 within the mold body. In one preferred embodiment of the present invention the mold comprises a horizontal mold section having a channel in the matrix portion of the mold which channel is of the proper size to substantially enclose the runner tile so that when the tile is in position the end wall of the matrix is substantially smooth. The invention contemplates also, a mold wherein the ends thereof are symmetric in that each 30 end of the matrix portion is provided with a channel and with the channels being of the same size. One of the channels is adapted to receive a runner tile provided with an opening adjacent the lower end thereof and the 35 other channel is adapted to receive a gas outlet tile with the opening adjacent the upper end of the matrix portion. The body portion preferably is provided with slightly inclined sides to provide a draught for the removal of the ingot and the body portion may 40 be formed with an integral top or may be provided with a removable top cover through which the runner and gas outlet tiles may 45 extend. Where the cover is utilized preferably the draught of the mold is toward the cover. This facilitates the mold being relieved of the mold gases which may be driven out from the steel as the steel hardens in the mold since the upwardly and outwardly inclined sides tend to prevent any overhanging portions that might tend to trap mold 50 gases. The placing of runners in the mold in such manner that one side of the runner is a side wall of the ingot causes the molten steel in the mold to heat the runner so that there is substantially no liability of the runner being chilled and cracked by the unequal heating due to hot steel pouring through the runner. Furthermore if the runner should 55 crack very little damage is done because any

escaping steel pours directly into the mold and the mold body securely holds the runner parts in position if the runner should break into pieces. Since both tiles are within the mold body and adjacent the ingot, 70 both the runner and the gas outlet member leave the mold with the ingot so that the mold is completely cleaned or cleared when the ingot is stripped therefrom. In view of the fact that the gas outlet and the runner 75 are as closely associated with the ingot as is possible it follows that the amount of scrap attached to the ingot is reduced to a minimum, and that this scrap need not be broken away before the ingot can be handled. 80

Referring now to the drawings which disclose one embodiment of the present invention the body portion 1 is provided adjacent each end thereof with channels 2 and 4 in which a runner tile 5 and a gas outlet 6 are respectively set. The runner tile is provided with an opening 7 comprising a vertical portion and a horizontal portion leading into the matrix 8 adjacent the lower part thereof. The gas outlet 6 is provided with an opening 9 which enters the matrix adjacent the upper part thereof. The passageway in the gas outlet below the entrance to the matrix may be filled with suitable luting clay 10 or other material in order to 95 save scrap. The side walls of the body portion of the mold are preferably slightly inclined as is indicated in Figures 3, 4 and 5 in order to provide draught for removing the ingot from the body portion. The ends of the body portion may be provided with crane hubs 11 or other suitable means for permitting the handling of the body by a suitable crane. In the preferred form the body portion is provided with a cover 12 which may be slotted at one end as at 14 to provide an opening for the runner tile and may be slotted at the other end as at 15 to provide an opening for the gas outlet tile. A suitable fountain 16 is adapted to 100 be set over the runner tile and to comprise a funnel for delivering molten steel into the runner. It will be noted that the cover as well as the body portion is symmetric in 105 form and therefore it is not necessary to observe any particular relation in which these members are set so long as one is properly placed in position over the other. 110

The mold is adapted to be set on a suitable stool 17 at which time is is ready for pouring operations. By this construction it will be noted that all sides of the ingot are adapted to be chilled and the steel is adapted to be introduced into the mold adjacent the bottom thereof, while the gases are adapted to escape from the opposite end and adjacent the upper portion thereof, and that the runner tile and gas outlet are both within the body portion of the mold so that floor 115 space is conserved. 120

Having thus described my invention, what I claim is:

1. An ingot mold comprising in combination a body portion, a cover for said body portion and provided with a notch to receive a runner tile, said body portion being provided in the end thereof with a channel adapted to receive a runner tile in such manner that the walls of the channel support the runner tile, a runner tile in said channel and extending through said cover, and the inner facing of the runner tile comprises a portion of the matrix wall.

2. An ingot mold comprising in combination a chill body portion, a chill cover for said body portion and provided with notches at both ends thereof, said body portion being provided in both ends with channels adapted to receive tiles in such manner that the walls of the channels support the tiles, tiles in said channels and extending into said notches, and the inner facings of the tiles comprise portions of the matrix wall.

3. An ingot mold comprising in combination a chill body portion, a chill cover, said body portion being provided in both ends thereof with channels adapted to receive tiles in such manner that the walls of the channels support the runner tiles and the inner facings of the tiles comprise portions of the matrix wall with one tile comprising a runner conduit and the other tile comprising a gas outlet.

4. An ingot mold comprising in combination a chill body portion, a chill cover for said body portion, said body portion being provided in both ends thereof with channels adapted to receive tiles in such manner that the walls of the channels support the tiles and the inner facing of the tiles comprise portions of the matrix wall with one tile comprising a runner conduit and the other tile comprising a gas outlet and the runner opening into the lower part of the matrix and the outlet opening into the upper part of the matrix.

5. An ingot mold for casting steel ingots or the like comprising a body portion in the form of a shell-like member and having a matrix comprising side walls with the top and bottom thereof open, said body portion being provided with a channel in one end thereof and adapted to receive a runner tile provided with a conduit in such manner that one face of the tile comprises a portion of the matrix side wall, a cover adapted to close the top of said body portion, said cover having a notch in the end thereof and over said channel when the cover is in position on the body, and a bottom plate adapted to close the bottom side of said body portion.

6. An ingot mold for casting steel ingots or the like comprising a body portion in the form of a shell-like member and having a

matrix comprising side walls with the top and bottom thereof open, said body portion being provided with channels in both ends thereof and adapted to receive a runner tile and a gas outlet tile each provided with a conduit in such manner that one face of each tile comprises a portion of the matrix side wall, a cover adapted to close the top of said body portion, and a bottom plate adapted to close the bottom side of said body portion.

7. An ingot mold for casting steel ingots or the like comprising a body portion in the form of a shell-like member and having a matrix comprising side walls with the top and bottom thereof open, said body portion being provided with channels in both ends thereof and adapted to receive a runner tile and a gas outlet tile each provided with a conduit in such manner that one face of each tile comprises a portion of the matrix side wall, a cover adapted to close the top of said body portion, said cover being provided with notches to receive said tiles, and a bottom plate adapted to close the bottom side of said body portion.

8. An ingot mold for casting steel ingots or the like comprising a body portion in the form of a shell-like member and having a matrix comprising side walls with the top and bottom thereof open, said body portion being provided with channels in both ends thereof and adapted to receive a runner tile and a gas outlet tile each provided with a conduit in such manner that one face of each tile comprises a portion of the matrix side wall, a cover adapted to close the top of said body portion, said cover being provided with notches to receive said tiles, said cover and said body each being symmetric as to both ends thereof, and a bottom plate adapted to close the bottom side of said body portion.

9. An ingot mold for casting steel ingots or the like comprising a body portion having a matrix opening therein, channels in each end of said body portion and adapted to receive tiles, tiles in said channels and each provided with a conduit having a vertical portion and a horizontal portion connected therewith in such manner that when said tiles are in position they are adapted to support pressure of the molten steel and one side of each tile is adapted to form a portion of the matrix wall.

10. A mold for casting horizontal ingots comprising an open trough shaped chill body, a channel extending along one end thereof, a cover for the body having a notch in alignment with said channel, and a runner tile fitted to said channel and extending through the notch.

11. A mold for casting horizontal ingots comprising an open trough shaped chill body, an open channel extending along one

end thereof, a cover for the body having a notch in alignment with said channel, and a runner tile supported by the walls of said channel and extending through the notch.

5 12. A mold for casting horizontal ingots comprising an open trough shaped chill body a relatively narrow channel extending vertically along one end thereof, a cover for the body having a notch in alignment with 10 said channel and a runner tile fitted to said channel to form a portion of the end wall of the matrix and extending through the notch.

13. A mold for casting horizontal ingots comprising in combination, a chill body portion 15 entirely surrounding a horizontal matrix, a channel extending through one end of said body portion, and a runner tile mounted in said channel and supported thereby.

14. A mold for casting horizontal ingots 20 comprising in combination, a chill body portion entirely surrounding a horizontal matrix, a channel extending through one end of said body portion, and a runner tile mounted in said channel and supported 25 thereby, one side face of said runner tile forming a part of the wall of the matrix.

15. A mold for casting horizontal ingots comprising in combination, a chill body portion 30 entirely surrounding a horizontal matrix, a channel extending through one end of said body portion, and a relatively narrow runner tile, mounted in said channel and supported thereby, one side face of said runner tile forming a part of the wall of the 35 matrix.

ALBERT E. ABEL.
